UNITED STATES PATENT OFFICE.

JOHN C. CASEY, OF CINCINNATI, OHIO.

WOODWORKING MACHINERY.

1,081,578.

Specification of Letters Patent. Patented Dec. 16, 1913.

Application filed August 22, 1912. Serial No. 716,449.

To all whom it may concern:

Be it known that I, JOHN C. CASEY, a citizen of the United States, residing at Cincinnati, in the county of Hamilton and State of Ohio, have invented certain new and useful Improvements in Woodworking Machinery, of which the following is a specification.

My invention relates to wood-working machinery intended primarily for operation on building timbers or boards, and especially applicable in cutting the angular inner ends of rafters employed in constructing so-called hip-roofs, the inner ends of such rafters being cut at an angle across the width and 15 at an angle across the thickness of the timber.

My invention is also applicable in other relations.

My invention has for its object the provision of novel means whereby a circular saw-blade may be adjusted into various positions for presenting its axis of rotation simultaneously at an angle to a horizontal plane and at an angle to a vertical plane, so that a 20 board or timber positioned lengthwise of the machine may be simultaneously cut at angles across its width and thickness.

It is a further object of my invention to provide means whereby the saw-mandrel and the stock-supporting table may be simultaneously and correlately shifted for adjustment of the parts; further to provide novel means for mounting the table and saw-mandrel for interdependently adjusting the 25 same; further to provide novel means for supporting and guiding the stock; further to provide novel combination of means whereby a reciprocating saw-blade may be employed on my improved device; and further to provide novel means whereby various 30 operations may be performed upon the same timber or board.

The invention will be readily understood from the foregoing, and from the following 35 description and claims, and from the drawings, in which latter:

Figure 1 is a side elevation of my improved device partly broken away. Fig. 2 is a plan view of the same. Fig. 3 is an 40 end elevation of the same, viewing the same from the saw end of the machine, the saw-blade being partly broken away. Fig. 4 is an end elevation of the same, viewing the same from the boring end of the machine. Fig. 5 is a plan section on the line 5—5 of Fig. 3, showing the manner of mounting the

mandrel-housing, the table, and saddle for the latter. Fig. 6 is a vertical section on the line 6—6 of Fig. 5. Fig. 7 is a rear elevation showing the adjusting means for the 60 mandrel-housing and table. Fig. 8 is a vertical section of the same, taken on the line 8—8 of Fig. 3, partly broken away, the saw-mandrel being however shown adjusted to inclination and the table in rear position. Fig. 9 is a detail in plan section on the line 9—9 of Fig. 1. Fig. 10 is a detail in vertical section on the line 10—10 of Fig. 3, showing the cranking mechanism with the connecting link for the scroll-saw mechanism in place. Fig. 11 is a cross-section of the same on the line 11—11 of Fig. 10. Fig. 12 is a vertical section on the line 12—12 of Fig. 3, showing the cushioning means for the supporting axle. Fig. 13 is a vertical section taken on the line 13—13 of Fig. 3, with a cutter-head substituted for the saw-blade on the mandrel. Fig. 14 is a side elevation of the saw-end of the machine, partly broken away, showing the 80 scroll-saw in position. Fig. 15 is a side elevation of the beveled end of a hip-roof rafter; and, Fig. 16 is an edge elevation of the same.

15 represents the main frame of the machine supported on suitable wheels 16, 17. The wheel 16 is journaled on an axle 18 supported in bearings 19 in a yoke 20 having an upright stem 21 journaled in a bearing 22 on the main frame, a pull-yoke 23 being 90 looped about the axle 18. A suitable pulling-agency may be hitched to this pull-yoke for moving the machine from place to place. The wheels 17 are mounted on an axle 24 movable up and down in slots 25 of bearings 26 and cushioned by springs 27 in sockets 28, set-screws 29 threaded in said bearing being arranged to impinge polygonal portions 24' of the axle 24 for rigidly 95 positioning the main frame with relation to the axle during operation of the machine.

31 is a drive-shaft journaled in a bearing 32 of the main frame. This drive-shaft is driven in suitable manner and is shown as the crank-shaft of an internal combustion 105 motor, the crank 33 thereof being operated in well-known manner from the internal combustion motor 34.

41 is a mandrel arranged to support a suitable wood-cutting agency, primarily a 110 circular saw-blade 42. This mandrel is arranged to be angularly adjusted in a verti-

cal plane and also in a horizontal plane, and is arranged to be adjusted into various tilted positions with relation to both said planes. Driving means are provided therefor in such manner as to maintain driving relation between the drive-shaft and the mandrel throughout the various adjustments of the latter, the latter being so arranged also as to permit adjustment of a stock-supporting table located adjacent to said saw-blade.

45 is a table-saddle pivoted upon the main frame and arranged to be adjusted in a horizontal plane. The saw-mandrel is arranged to be moved with the table-saddle in 15 this last-named adjustment.

46 is a table movable back and forth on the table-saddle on guide-ways 47, and held in line by a rib 48 on the saddle received in a groove 50 on the frame of the table.

20 51 is a bevel-gear on the drive-shaft 31.

52 is a trunnion-sleeve fixed in a bearing 53 on the table-saddle and journaled in a bearing 54 in the main frame.

25 55 is an upright shaft journaled in the trunnion-sleeve. It has a bevel-gear 56 fast thereon at its lower end meshing with the bevel-gear 51 and a bevel-gear 57 fast thereon at its upper end.

58, 59, are bearings on the table-saddle. 30 60 is a mandrel-housing having a bearing sleeve 61 journaled in the bearings 58.

62 is a shaft journaled in the bearing sleeve. This shaft has a bevel-gear 63 fast thereon which meshes with the bevel-gear 35 57 and a bevel-gear 64 fast thereon which meshes with a bevel-gear 65 fast on the mandrel 41, the mandrel being journaled in bearings 66, 67, on said housing.

68 is a rock-shaft journaled in the bearing 40 59 and secured as by a pin 69 to the mandrel-housing 60 for rocking the mandrel-housing and adjusting the saw-mandrel into suitable angular position in a vertical plane with relation to the surface 70 of the table.

45 The bevel-gears 51 and 56 are mounted in an oil-tight box 71, the bevel-gears 57 and 63 are mounted in an oil-tight box 72, and the bevel-gears 64 and 65 are mounted in an oil-tight box 73.

50 When the saw-mandrel is adjusted in a vertical plane it is desirable that the table be also adjusted toward and from the saw-blade so as to maintain close proximity of the table with relation to the saw-blade. I 55 provide adjusting means whereby simultaneous adjustment is imparted to the mandrel and the table.

75 is a segment-arm rigidly secured to the rock-shaft 68. It is moved by a handle 76 60 and clamped by a clamp-screw 77 having threaded connection 78 with the saddle, passing through an arc-slot 79 in said segment-arm.

82 is a bell-crank lever pivoted on a bolt 65 83 in the table-saddle.

85 is a link articulated respectively at 86, 87, with the rear end of the housing and the arm 88 of the bell-crank lever 82. The arm 89 of said bell-crank lever is provided with a knob 90 received in a slot 91 in the frame 70 of the table.

When now the segment-arm 75 is rocked, it rocks the mandrel-housing, which through the medium of the link 85 and bell-crank lever 82, slides the table-frame back and forth in unison with the rocking adjustment 75 imparted to the mandrel-housing, thereby maintaining the proper relative positions between the saw-blade and table throughout the various adjustments of the parts. After 80 adjustment of the parts, the segment-arm is clamped to the saddle, thereby simultaneously locking the mandrel-housing in its angular position and the table-frame in its shifted position upon the saddle. 85

For adjusting the saw-mandrel in a horizontal plane, the saddle 45 is swung about its pivot formed by the trunnion-sleeve 52, the swinging end of the saddle being slideable upon a guide-way 95 shown on an arc-piece 90 secured to the main frame of the machine.

96 is a clamp for clamping the saddle in adjusted position. When the saddle is adjusted it carries the superposed table and the mandrel with it, the bevel-gear 63 moving about the bevel-gear 57 in this adjustment for maintaining the driving relation between the drive-shaft and the mandrel. During rocking movement of the mandrel-housing, driving relation between the bevel-gears 64 and 65 is also maintained. 100

The table is provided with a slot 101 extending at right angles to the axis of rotation of the saw-mandrel. The slide-piece 102 of a saw-fence 103 is received and slideable in this slot. The end of the timber or board to be cut is supported on this table and moved by the saw-fence when it is desired to cut the same. 105

An auxiliary table is provided for supporting the overhanging end of the timber or board, this latter table being preferably mounted on rollers and movable on a track arranged to be adjusted parallel to the slot 101. Thus 105 is an auxiliary table provided 110 with rollers 106 movable on guide-ways 107 on a table-support 108 having an upright trunnion 109 in a bearing 110 in the main frame. There is a scale 111 between the auxiliary table and the table-support. There is 115 further a scale 112 between the table-saddle 45 and the main frame so arranged that the main and auxiliary tables are conveniently adjusted to similar angles. There is further a scale 113 between the arm 75 and the main table parts for determining the angle of adjustment of the saw-mandrel in a vertical plane. 120

A supplemental table may be provided on the main table 46, shown by the overhanging 125

table 116 movable up and down by adjusting screws 117 on guides 118 between the main and supplemental tables. A saw-slot 119 is provided between the main and supplemental tables.

If desired, a short cutter-head 120 may be substituted for the saw-blade, the cutter-head being received through an opening 121 in the supplemental table normally closed by a plate 122. For convenience of attaching the saw-blade and cutter-head and preventing interference between the saw-mandrel and the supplemental table, when the saw-mandrel is adjusted in a vertical plane, I provide interchangeable stems 123, 124, on which the saw-blade and cutter-head are respectively mounted, the stems forming part of the mandrel and being received through a bore 125 therethrough and clamped in place by a clamp-nut 126.

The mandrel may be adjusted in a vertical plane or in a horizontal plane or in both said planes for presenting the cutting agency at various angles to the timber. Means are also provided for edging up the timber by means of the cutter-head, and I have further provided means for boring holes in the timber, so that the various operations to be performed on a timber of the character stated may be performed on this combined machine.

The drive-shaft has a sleeve 131 received thereabout, the sleeve having spline-connection 132 with said shaft, and being slidable lengthwise in a bearing 133 on the main frame. The sleeve has a socket 134 at its outer end, in which a boring-bit 135 is arranged to be secured. 136 is a table on which the timber is arranged to be placed against bars 137. 138 is an upright post having rack-teeth 139 formed thereon, the post having the table 136 secured thereto. The post is slidable up and down in a bearing 140 of the main frame, and is moved by means of a pinion 141 on a shaft 142 journaled in a bearing 143 on the main frame and having an arm 144 secured thereto. 145 is a plate provided with apertures 146 with which a pull-pin 147 on the arm 144 is adapted to coöperate for positioning the height of the table 136. 151 is a bell-crank lever pivoted at 152 on a bracket 153 extending from the plate 145. 154 is a pin on the bell-crank lever received in an annular slot 155 of the sleeve 131. 156 is an operating lever pivoted at 157 to the plate 145 and articulated at its inner end to the bell-crank lever 151, this latter articulation being shown as a slot 158 on the operating lever in which a pin 159 on the bell-crank lever is received. The operation of the operating lever moves the sleeve 131 and the boring-bit secured thereto in and out with relation to the stock supported on the table 136, the position of the hole bored in this stock being determined by the height of said

table and the position of the stock lengthwise thereof.

161 is a starting handle for the shaft of the internal combustion motor, and is provided with usual throw-out mechanism 70 shown as a pin 162 received in a slot 163 having an inclined bottom, the slot being in a crank-extension 164 of the drive-shaft and the handle located on said extension. The drive-shaft has a crank-disk 165 secured 75 thereto on which a crank-pin 166 is located, from which latter the crank-extension extends. The crank-disk may be provided with a slot 163' similar to the slot 163. The crank-pin and extension are releasable from the crank-disk, as by means of a bolt 167, lugs 168 on the crank-pin being received in a slot 169 in the crank-disk for positioning the extension relatively to the crank-disk. A connecting rod 171 is journaled with a 85 bearing 172 about the crank 166 and articulated at 173 with a pitman 174 having reciprocation in a bearing 175 on the saddle 45, the bearing 175 being releasable.

176 is a resilient arm extending from a 90 block 177 releasably secured to the table by a clamp 178, the block having a rib 179 thereon received in the slot 101 in the tabletop.

180 is a scroll-saw blade suitably secured 95 between the pitman 174 and the resilient or scroll-saw arm 176, the scroll-saw blade passing through the opening 181 in the tabletop.

Instancing an operation of my improved 100 device for cutting the bevels at the ends of rafters employed in constructing so-called hip-roofs, I have illustrated a rafter of this kind at 185 in Figs. 15 and 16. The rafter is provided with a bevel 186 extending crosswise of its width and with a bevel 187 extending crosswise of its thickness. The bevel 186 is arranged to compensate for the upwardly sloping position of the rafter with relation to the stringer to which it is secured, and the bevel 187 is arranged to compensate for the angular position of the stringer crosswise of the roof, the two bevels forming a compound bevel. For cutting the bevel 186 the saw-mandrel is swung 110 sidewardly for presenting the axis of rotation of the mandrel at an angle in a horizontal plane to the axis of rotation of the drive-shaft, this being accomplished by swinging the table-saddle upon its pivot on the main frame. For adjusting the saw-blade so as to cut the bevel 187 the outer end of the mandrel is swung upwardly so as to present its axis of rotation at an angle in a vertical plane to the axis of rotation of the drive-shaft. This is accomplished by manipulation 120 of the arm 75. When cutting the timber for this purpose it is laid crosswise upon the main table and upon the auxiliary table, which latter has also been adjusted to angu- 130

lar position, the timber being positioned parallel to the drive-shaft. It is then pushed crosswise of the table by means of the saw-fence, this movement also causing 5 the timber to move lengthwise of a drive-shaft, for feeding the end of the board through the saw-blade and providing it with the compound bevel stated. The same timbers may also have their edges planed by 10 the cutter-head, and provided with holes and slots by means of the boring-bit and scroll-saw.

It is of course obvious that other cutting operations may be performed on the 15 machine.

Having thus fully described my invention, what I claim as new and desire to secure by Letters Patent, is:

1. In a circular saw machine, the combination of a material-support having a substantially horizontal material-supporting surface, a mandrel journaled under the horizontal plane of said material-supporting surface, said mandrel arranged for having 20 a circular saw-blade attached thereto projecting above said last-named plane into operative positions, and means for adjusting said mandrel at an angle to a horizontal plane and at an angle to a vertical plane 25 30 for adjusting said circular saw-blade into said operative positions whereby material

on said material-supporting surface is cut crosswise at angles both to its sides and edges by coöperative cutting movement between said saw-blade and material. 35

2. In a circular saw machine, the combination of a material-support having a substantially horizontal material-supporting surface, a mandrel arranged for having a circular saw-blade attached thereto, means 40 for adjusting said mandrel at angles to a horizontal plane and at angles to a vertical plane, and for rotatively adjusting said material-support in its plane during adjusted positions of said mandrel at angles to said 45 horizontal plane, for the purpose described.

3. In a circular saw machine, the combination of a circular saw-blade, a material-support through which said circular saw-blade projects from below into operative positions, and means for adjusting said circular saw-blade at inclinations to both horizontal and vertical planes into said operative 50 positions.

In testimony whereof, I have hereunto 55 subscribed my name in the presence of two subscribing witnesses.

JOHN C. CASEY.
